UNITED STATES PATENT OFFICE.

FREDERICK ROETTGES, OF STAMFORD, CONNECTICUT, ASSIGNOR TO WILLIAM R. NOE & SONS, A COPARTNERSHIP OF NEW YORK CITY.

DESIGN FOR A CANDLESTICK.

Application filed May 11, 1923. Serial No. 6,137. Term of patent 7 years.

To all whom it may concern:

Be it known that I, FREDERICK ROETTGES, a citizen of the German Republic, and resident of Stamford, in the county of Fairfield and State of Connecticut, have invented a new, original, and ornamental Design for Candlestick, of which the following is a specification, reference being had to the accompanying drawing, forming part thereof.

Fig. 1 is a side elevation of candlestick, showing my new design.

Fig. 2 is a plan view of the top of the candle cup taken on the line 1—1 and looking in the direction of the arrows, showing the contour of the cup to be round, also

showing one half of the surface ornamentation on the cup, it being understood that the other half of ornamentation is identical.

Fig. 3 is a plan view of the base taken on the line 2—2 and looking in the direction of the arrows showing that the contour of the base is round, also showing one quarter of the surface ornamentation on the base, it being understood that the remainder of the ornamentation is identical.

I claim:

The ornamental design for a candlestick, as shown.

FREDERICK ROETTGES.
